CONTROL VALVE FOR GASEOUS FUEL
BURNERS

Charles M. Mayer, Mansfield, Ohio, assignor to
The Tappan Stove Company, Mansfield, Ohio,
a corporation of Ohio

Application October 7, 1944, Serial No. 557,608

6 Claims. (Cl. 277—32)

1

This invention relates generally to a control valve for controlling the flow of gas to a gas burner and more particularly to a control valve for the top burners of a gas range which is so designed and constructed as to make it possible to obtain either a full flame or a simmer flame at the gas burner.

One of the objects of the invention is to provide a control valve of the character described which will permit accurate control of the gas admitted to a burner whether the burner venturi is located at or immediately adjacent the valve, or in a remote location and connected by a tube or pipe. Such a valve is particularly desirable with hydrocarbon gases which are delivered at relatively high pressure and at high heat content per unit volume. For example, enough gas is delivered through an orifice having a diameter of .025 inch to support a maximum cooking flame on a top burner. For many cooking operations, it is desired to have a reduced flame and even a very small flame for simmering. For a simmer flame, the gas flow is that permitted through an orifice of about .009 to .012 inch in diameter or an equivalent gas passageway. Obviously, if this control is attempted by the partial registration of two ports located in the plug and body of the valve respectively, the slightest rotation of the plug would at this point enlarge or decrease the opening by a large percentage in comparison to the small total gas flow required. The control of the flame therefore becomes very critical and requires only a slight turn of the handle from the "off" to "full" position. In my improved valve, I control the flow of gas by means of a longitudinally movable valve member which is actuated by rotation of the valve cock so as to obtain accurate adjustment and any size flame that is desired without minute adjustment.

Another object of the invention is to provide a gas control valve having the above described distinguishing features and characteristics and which comprises few parts which are well adapted for production and assembly at a minimum cost.

Further and more limited objects of the invention will appear as the description proceeds and by reference to the accompanying drawings in which:

Fig. 1 is a vertical sectional view disclosing my improved control valve together with a top burner for a gas range;

Fig. 2 is a vertical sectional view of the control valve proper;

Fig. 3 is a vertical sectional view on the line 3—3 of Fig. 2;

2

Fig. 4 is a view in elevation of the longitudinally movable valve member;

Fig. 5 is a sectional view on the line 5—5 of Fig. 4;

5 Fig. 6 is a fragmentary view in elevation taken on the line 6—6 of Fig. 2;

Fig. 7 is a vertical sectional view taken on the line 7—7 of Fig. 2;

10 Fig. 8 is a vertical sectional view taken on the line 8—8 of Fig. 2; and

Fig. 9 is a fragmentary sectional view similar to Fig. 2, but showing the valve in the simmer position.

Referring now to the drawings, the control valve consists essentially of a valve body member 1 having an inlet passageway 2 and an outlet passageway 3. The valve body has a generally frusto-conical chamber therein into which fits a similar shaped valve plug 4 which is actuated by a valve stem 5 and a handle 8. A cap 9 closes the end of the valve body and a coil spring 10 tends to urge the plug toward the left as seen in Fig. 2. The plug 4 has one or more ports 11 therein adapted to be brought into register with the outlet passageway 3. The valve plug 4 is provided at its inner end with a circular recess 12. Threadedly secured in the inlet passageway 2 is a valve member 13 which is shown in detail in Figs. 4 and 5. One end of the valve member 13 fits within the recess 12 and is slidably but non-rotatably secured therein. The valve member 13 is provided with an axial bore 14 and a smaller intersecting radial bore 15 the purpose of which will hereinafter appear. The inner end portion 30 of the valve member 13 fits within notches provided within the wall of the chamber 12 so that a turning movement of the valve stem 5 imparts a longitudinal movement of the valve member 13 due to its threaded engagement with the walls 40 of the inlet passageway.

Threadedly secured within the end of the inlet passageway is a plug 16 having therein an axial bore 17 which is disposed in axial alignment with the bore 14 in the valve member 13. 45 A pipe 18 connects the inlet passageway with the gas intake manifold 19.

In Fig. 2 the valve is shown in the position for permitting a maximum flame at the burner which is determined by the size of the bore 17. Due to the fact that the valve member 13 is somewhat triangularly shaped in section, three passageways are provided between the inner wall of the inlet passage and the valve member through which the gas may flow. When the valve is moved to the position shown in Fig. 2, gas flows through the

port 17 in the plug 16 and thence along the valve member into the chamber 12 and thence through the outlet passage 3 through the port 11. In this position of the valve, the burner is receiving the maximum amount of gas permitted which is determined by the size of the bore 17. When the valve is moved to the simmer position shown in Fig. 9, the valve member 13 abuts the machined face of the plug 16 and completely shuts off the flow of gas between the faces of these parts. In the simmer position of the valve, the gas will flow through the bore 17, thence through the bore 14, thence through the smaller radial bore 15 into the chamber 12 and thence through the port 11 and outlet passage 3. The port 15 is of such size as to permit the flow of only sufficient gas to maintain a simmer flame. In the "off" position of the valve the outlet is closed by a solid portion of the plug 4. The first 90-degree turn of the valve plug 4 from the "off" position brings the parts to the full "on" position shown in Fig. 2. If the valve handle is moved 90 degrees further in the same direction, the face of the valve member 13 is moved into engagement with the face of the plug 17 so as to permit flow of gas only through the ports 14 and 15 to provide a simmer flame. In Fig. 1 there is disclosed a flat top stove 20 having the top burner 21 disposed immediately above the control valve but this arrangement is only illustrative as the control valve may be located elsewhere.

It will now be clear that I have provided a control valve for gas burners which will accomplish the objects of the invention as hereinbefore stated. The embodiment of the invention herein disclosed is to be considered merely as illustrative and not in a limiting sense as various changes may be made in the details of construction and arrangement of parts without departing from the spirit of my invention. The invention is therefore limited only in accordance with the scope of the appended claims.

Having thus described my invention, what I claim is:

1. A control valve for gas burners comprising a valve body having an internally threaded inlet passageway and an outlet passageway, a plug secured in the outer end of said inlet passageway, an axial bore extending through said plug, an externally threaded valve member screwed into the inner end of said inlet passageway, a longitudinal bore extending partially through said valve member in axial alignment with the bore in said plug, means providing for the flow of fluid extending throughout the length of said valve member, a radial bore in said valve member providing communication between said longitudinal bore and said means, said radial bore being of smaller capacity than said longitudinal bore or said means, and means for rotating said valve member to move the outer face of said valve member into and out of engagement with the inner face of said plug whereby in one position the axial bore in said plug determines the amount of gas flowing into said valve body and in the other position the radial bore in said valve member determines the amount of gas flowing into said valve body.

2. A control valve for gas burners comprising a valve body having an inlet and an outlet passageway, a plug secured in the outer end of said inlet passageway, an axial bore of fixed capacity extending through said plug, a valve member mounted in the inner end of said passageway and adapted to be moved into and out of engagement

with the inner end of said plug, a longitudinal bore extending partially through said valve member in axial alignment with the axial bore through said plug, means in said valve member providing for the flow of fluid, said means extending throughout the length of said valve member and the capacity thereof being not less than the capacity of the axial bore in said plug, a communicating radial bore between said longitudinal bore and said means in said valve member of smaller capacity than the capacity of said axial bore in said plug, and rotatable means for moving said valve member into and out of engagement with the inner face of said plug whereby in one position the axial bore in said plug determines the amount of gas flowing into said valve body and in the other position the radial bore in said valve member determines the amount of gas flowing into said valve body.

20 3. A control valve for gas burners comprising a valve body having an inlet and an outlet passageway, a plug secured in the outer end of said inlet passageway, an axial bore of fixed capacity extending through said plug, a valve member mounted in the inner end of said passageway and adapted to be moved into and out of engagement with the inner end of said plug, means in said valve member providing for the flow of fluid through which gas is adapted to flow into said 25 valve body when said valve member is out of engagement with the inner face of said plug, said means being of a capacity not less than the capacity of the axial bore in said plug, a bore in said valve member of smaller capacity than the 30 capacity of the axial bore in said plug through which all the gas entering said valve body flows when said valve member is in engagement with the inner face of said plug, and manually operated means for moving said valve member into 35 and out of engagement with the inner face of said plug.

40 4. A control valve for gas burners comprising a valve body having an internally threaded inlet passageway and an outlet passageway, a plug secured in the outer end of said inlet passageway, an axial bore of fixed capacity extending through said plug, an externally threaded valve member screwed into the inner end of said inlet passageway and adapted to be moved into and out of 45 engagement with the inner end of said plug, means in said valve member providing for the flow of fluid through which gas is adapted to flow into said valve body when said valve member is out of engagement with the inner face of said 50 plug, said means being of a capacity not less than the capacity of the axial bore in said plug, a bore in said valve member of smaller capacity than the capacity of the axial bore in said plug through which all of the gas entering said valve 55 body flows when said valve member is in engagement with the inner face of said plug, and manually operated means for rotating said valve member to move the outer face of said valve member into and out of engagement with the inner face of said 60 plug.

65 5. A control valve for gas burners comprising a valve body having an inlet and an outlet passageway, a plug secured in the outer end of said inlet passageway, an axial bore of fixed capacity extending through said plug, a valve member mounted in the inner end of said passageway and adapted to be moved into and out of engagement with the inner end of said plug, means in said valve member providing for the flow of fluid 70 through which gas is adapted to flow into said 75

valve body when said valve member is out of engagement with the inner face of said plug, said means being of a capacity not less than the capacity of the axial bore in said plug, a bore in said valve member of smaller capacity than the capacity of the axial bore in said plug through which all the gas entering said valve body flows when said valve member is in engagement with the inner face of said plug, a plug valve rotatably mounted in said valve body and operative to control the flow of gas through said outlet passageway, and interconnecting means between said valve member and said plug valve through which said valve member is moved into and out of engagement with said plug by the rotation of said plug valve.

6. A control valve for gas burners comprising a valve body having an internally threaded inlet passageway and an outlet passageway, a plug secured in the outer end of said inlet passageway, 20 an axial bore extending through said plug, an externally threaded valve member screwed into the inner end of said inlet passageway, a longitudinal bore extending partially through said valve member in axial alignment with the bore in said plug, means providing for the flow of fluid extending throughout the length of said valve member, a radial bore in said valve member providing communication between said longitudinal bore and said means, said radial bore being of smaller capacity than said longitudinal bore or said means, a plug valve rotatably mount-

ed in said valve body and operative to control the passage of gas through said outlet passageway, interconnecting means between said valve member and said plug valve through which said valve member is rotated in unison with said plug valve and moved into or out of engagement with the inner face of said plug whereby the axial bore in said plug controls the amount of gas flowing into said valve body when said valve is 10 out of engagement with said plug and the radial bore in said valve member controls the amount of gas flowing into said valve body when said valve member is in engagement with said plug.
